CLAIM

The ornamental design for the pegboard mounted support for displaying power tools, substantially as shown and described.

DESCRIPTION

FIG. 1 is a front perspective view of a pegboard mounted support for displaying power tools, showing our new design;

FIG. 2 is a top plan view;

FIG. 3 is a bottom plan view;

FIGS. 4, 5 and 6 are elevational views as seen generally from lines 4—4, 5—5, and 6—6 in FIG. 2; and

FIG. 7 is a rear elevational view.
